(57) **CLAIM**

The ornamental design for a “personal digital assistant,” as shown and described.

DESCRIPTION

FIG. 1 is a top front and right side perspective view of a personal digital assistant according to our design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a bottom plan view thereof;

FIG. 7 is a top plan view thereof;

FIG. 8 is a view similar to FIG. 1 illustrating the keyboard cover in an open condition;

FIG. 9 is a front elevational view thereof;

FIG. 10 is a rear elevational view thereof;

FIG. 11 is a left side elevational view thereof; and,

FIG. 12 is a right side elevational view thereof.

Bottom and top views of the personal digital assistant hereof in the open condition of FIGS. 8-12 are identical to the bottom and top views thereof illustrating FIGS. 6 and 7 respectively.
